TEACHING MACHINE

Jack Fairchild Fleming, Summit, N.J., assignor to
Sterling Plastics Co., Union, N.J., a corporation of
New Jersey

Filed Feb. 13, 1962, Ser. No. 68,793

Term of patent 14 years

(Cl. D25—1)

Fig. 2

Fig. 1

Fig. 5

Fig. 3

Fig. 4

FIG. 1 is a top view of a teaching machine embodying my new design with a corner of the top sheet of the writing slate curled for illustrative purposes only;

FIG. 2 is a side elevational view thereof as seen from the right of FIG. 1, the side opposite thereto being similar in appearance;

FIG. 3 is a front elevational view of the design as shown in FIG. 1;

FIG. 4 is a rear elevational view thereof; and

FIG. 5 is a bottom perspective view thereof.

My design comprises a casing of the configuration shown having on its top knurled wheels and the framed panel member of which the upper portion constitutes a window or viewing port for displaying information and the lower portion constitutes a slate or writing surface, substantially as shown.

I claim:

The ornamental design for a teaching machine, substantially as shown and described.
